UNITED STATES PATENT OFFICE.

ANTON ZWIEBEL, SR., OF BURLINGTON, WISCONSIN.

WINDOW-LOCK.

SPECIFICATION forming part of Letters Patent No. 761,747, dated June 7, 1904.

Application filed August 14, 1903. Serial No. 169,492. (Model.)

To all whom it may concern:

Be it known that I, ANTON ZWIEBEL, Sr., a citizen of the United States, residing at Burlington, in the county of Racine and State of Wisconsin, have invented certain new and useful Improvements in Window-Locks, of which the following is a specification.

This invention comprises a peculiar form of a locking device intended in its adaptation for use upon windows to prevent opening thereof, though applicable in various other ways in its locking capacity.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view showing the invention applied to a window for locking sash thereof. Fig. 2 is a view looking from the under side of the casing of the device, showing more particularly the exact construction of the latch-bolt. Fig. 3 is a detail perspective view 30 of the latch-bolt.

Corresponding and like parts are referred to in the following description and indicated in all the views of the drawings by the same reference characters.

The locking device is preferably applied to the upper side of the uppermost cross-bar of the lower sash 1, and consists of three parts only. The parts aforesaid are the casing 2, latch-bolt 3, and spring 4. The latch-bolt 3 is adapted for a slidable movement transversely of the casing 2, being mounted thereon so as to pass through openings 5, located upon corresponding sides of the said casing. A finger-piece 6 is formed upon one end of the latch-bolt and serves as means for operating the latter, so as to dispose same in or out of lock engagement relative to the upper sash 7. The latch-bolt 3 is also provided with a lock-bar 8, which is spaced from the latch-bar and disposed substantially in a parallel

relation thereto, and an opening 9 upon the casing receives the lock-bar, which moves within the casing on operation of the latch-bolt, and said opening directs the movement of the lock-bar in a manner readily apparent. In order to lock the latch-bolt in engagement with the upper sash and also to lock the same out of engagement therewith, the lock-bar is provided with notches 10, which engage the casing at a point adjacent to the opening 9 and hold the latch-bolt in the positions before mentioned upon operation of the bolt by means of the finger-piece 6. A stop-pin 11 is carried by the lock-bar 8, and the coil-spring 4 is disposed about the lock-bar intermediate the inner side of the casing and the aforesaid pin 11. The coil-spring 4 normally tends to hold the lock-bolt in engagement with the upper sash and at the same time exerts a lateral tension, so as to normally throw the notches 10 of the lock-bar into engagement with the casing. The coil-spring 4 thus exerts a longitudinal and lateral pressure upon the lock-bar, being especially advantageous for this reason. A base-plate 12 is used to close the open face of the casing, which is secured to the lower sash by means of screw-fastenings or the like. A number of recesses 13 are located upon the side member of the upper sash to receive the end of the latch-bolt, so as to lock the sash together. A reinforcing-plate 14, with openings corresponding to the recesses 13 relative to their disposition, is used to reinforce the said recesses for obvious reasons.

The lock device embodied in the invention is exceedingly simple as to the number of parts involved in this structure and constitutes a very efficient means for locking parts together. The liability of working the locking elements from locking engagement is entirely avoided, since the latch-bolt is held in positive engagement at all times when the same has been properly operated.

Having thus described the invention, what is claimed as new is—

1. In a lock, the combination of a casing, a lock-bar slidably mounted within the casing, lateral interlocking means between the lock-bar and casing to hold the lock-bar at any re-

quired position in its longitudinal movement, and a spring normally exerting a longitudinal and a lateral pressure upon the lock-bar, substantially as specified.

- 5 2. In a lock, the combination of a casing, a lock-bar slideable within the casing, interlocking means between the lock-bar and casing, a spring mounted upon the lock-bar and normally exerting a pressure thereon in the direction of its length and at a right angle to the longitudinal movement, a latch-bolt spaced

from and movable with the lock-bar and adapted to be projected beyond the casing and a finger-piece at the juncture of the lock-bar and latch-bolt, substantially as specified. ¹⁵

In testimony whereof I affix my signature in presence of two witnesses.

ANTON ZWIEBEL, Sr. [L. s.]
